STEEL FLUE BOILER

Gustav E. Olsen, Arverne, N.Y.

Application April 19, 1957, Serial No. 653,776

5 Claims. (Cl. 122—73)

This invention relates to boilers for use with steam and hot water heating systems and for heating hot water for domestic and process uses and more particularly concerns an improved steel boiler having provision for internal or external firing utilizing any suitable and convenient fuel such as oil, gas or coal. It comprises an improvement of my prior Patent No. 2,749,887 granted June 12, 1956.

With the rising cost of building construction it is essential to maintain the cost of materials used therein at the lowest possible level without sacrificing quality. This is particularly important in the case of heating systems for residences inasmuch as the mechanical equipment, its installation and subsequent operation comprise a substantial part of the cost and maintenance of the home. Accordingly, one object of the invention is to provide a novel and improved steel flue boiler capable of high operating efficiency with resultant fuel economy to the user and characterized by its simplicity of design and fabrication, dependability and relatively low manufacturing cost.

Another object of the invention resides in the provision of a novel and improved boiler utilizing a simple and effective arrangement of elements that may be fabricated of sheet metal with the minimum of fabricating machinery and labor and with resultant savings. The simplicity of design of the subject boiler is further characterized by the improved intercommunication of the waterways of the several water containing elements.

Still another object of this invention resides in the novel and improved combination and arrangement of boiler elements for steam boilers and hot water boilers that may be quickly and easily assembled to form a relatively light, strong, dependable and durable structure that will operate at high heat transfer rates and efficiencies with consequent fuel savings to the home owner or other user. By reason of the improved design of this boiler it may be fabricated to include provision for suitable fuel burning apparatus within the boiler itself or such fuel burning apparatus may be contained within a separate refractory-lined enclosure which may provide the support for the boiler on the boiler room floor.

Another object of the invention resides in the provision of a novel and improved internally-fired steel boiler of unusual compactness, occupying less than usual floor area for its installation and operation in the boiler room. By reason of an improved arrangement of the structural elements, the internal water and fire side surfaces are all readily accessible for inspection and cleaning and contribute to high operating efficiency and to low cost of maintenance in that damage which may result from clogged fire side and water side surfaces can be avoided.

A further object of the invention is the provision of a novel and improved boiler.

The above and other objects and advantages of the invention will become more apparent from the following description and accompanying drawings forming part of this application.

2

In the drawings:

Fig. 1 is a perspective view of one embodiment of a boiler in accordance with the invention;

Fig. 2 is an exploded perspective view of the boiler shown in Fig. 1;

Fig. 3 is a front view in partial section of the boiler shown in Fig. 1; and

Fig. 4 is a longitudinal cross sectional view of the boiler of Fig. 3 taken along the line 4—4 thereof.

10 The boiler in accordance with the invention comprises essentially several basic elements which may be assembled by conventional welding or other processes to form a completed unit. These elements include inner and outer shells which form the water spaces between the sides and the top chamber portions of the boiler, a flue barrel disposed within the confining firebox walls of the inner shell and comprising in effect a tubular water tank through which a plurality of flues extend for increasing the heat transfer efficiency of the boiler, front and rear transverse water circulating means attached to the under part of the flue barrel and circulating water thereto and to the water legs between the inner and outer shells and a front plate closing the front end of the boiler to cause combustion gases arising from the firebox to flow outwardly through the flues of the flue barrel and thence to the chimney. The boiler in accordance with the invention may also include suitable baffles to further deflect the gases upwardly and about the flue barrel and thence through the barrel to the chimney or other suitable external flue.

15 It will be apparent with reference to the drawings that this invention provides a relatively inexpensive, highly practical and completely dependable boiler applicable for both steam and hot water heating systems as well as for heating hot water for domestic and process uses and one that can be simply and easily fabricated of sheet steel plates with great economy of material, basic and simple machinery and without the need for highly trained personnel. The compactness of the subject boiler resulting in smaller dimensions and relatively light weight for its capacity contributes to easier handling in transportation and lower freight charges.

20 More specifically and with reference to the drawings the outer and inner shells of a boiler in accordance with the invention are denoted generally by the numerals 10 and 11, respectively. Both shells are of substantially similar configuration with the inner shell 11 being somewhat smaller in both width and height than the outer shell in order to provide side water legs 12 and a relatively large upper water chamber 13. The outer shell 10 in the illustrated embodiment of the invention includes a circular top portion 14 terminating in straight sides 15 and 16. One or more outlets 17 are provided in the top of shell 10 for the outward flow of steam or water as the case may be and the bottom edges of the walls 15 and 16 are provided with openings 18 for the connection of washout and return lines to the boiler.

25 The inner shell 11 as pointed out above is of a configuration somewhat similar to the outer shell 10 in that it is provided with a rounded top section 19 and substantially straight side walls 20 and 21. The radius of the top section 19 is smaller than the top 14 of the outer shell 10 and the side legs 20 and 21 are shorter than the legs 15 and 16 of the outer shell. In addition the inner shell 11 is further provided with a pair of flanges 20' and 21' formed integrally with the side walls 20 and 21, respectively, and of a width determined by the width of the outer shell so that they will form a bottom closure between the two shells as will be observed in Fig. 3. In some instances the bottom closure pieces may be narrow strips of steel at the bottom edges of the shells in place of the integral flanges.

To assemble the outer and inner shells the back edges of the shells 10 and 11 are placed in approximate alignment with the outer shell spanning the inner shell and the two shells welded together along the edges 22 and 23 to form a water tight seal. The front and back edges of the shells are later closed and sealed by plates 24 and 25, respectively, welded to the outer and inner shells to form the water tight compartments therebetween.

It will be observed that the inner shell includes front and rear openings 26 and 27 at the lower front and rear edges of the walls 20 and 21 in order to provide for the circulation of water through the transverse front and rear headers to be described. In addition the inner shell is provided with a top circulation opening 28 for communication between the flue barrel water space and the upper water chamber 13.

The flue barrel denoted by the numeral 29, comprises a tubular outer member 30 of a length approximately equal to but preferably longer than that of the outer shell 10. Within the tubular member 30 there are a plurality of flues or tubes 31 forming combustion gas passages. These flues may be of any desirable contour although flues of relatively narrow cross-section for increased heat transfer are preferred. Each flue 31 is preferably formed with pointed top and bottom for avoidance of sediment and air-bubble deposit and adherence and for improved water circulation past the bottom of the flue in an upward direction effecting a streamlining of an otherwise interfering surface at right angles to the flow of water. Each flue comprises a pair of side walls 32 have top and bottom portions 33 bent inwardly to form a pair of identical channel like members which when welded together along their top and bottom edges 33' form the completed flue. The flues may also in some instances be formed of one piece of plate appropriately flanged to the final shape thus giving but one joint to be welded or the component parts may consist of more than the two pieces first described depending upon fabricating equipment being used. The flues 31 are mounted within the barrel 30 by insertion through similarly contoured openings in the end flue head plates 37 and 38 at the ends of the flue barrel after which the end of the flues may be welded to the respective flue heads and the edges of the flue heads can be welded to the flue barrel to form a water tight chamber. The flue barrel is further provided with a top opening 39 to which a conduit 40 is welded for steam and water flow to the upper water chamber 13. In addition the flue barrel 29 is provided with one or more openings 41, 42 for water passage communication with the front and rear transverse water circulating headers.

The flue barrel is supported within and spaced from the inner shell 11 as shown in the figures and is attached to the transverse front and rear water header members generally denoted by the numerals 43 and 44, respectively.

These transverse water headers are substantially identical and therefore only the front header 43 will be described in detail.

This water header includes a pair of spaced parallel elements 45 and 46 with a closure base plate 47 which preferably extends outwardly beyond the plate 45 to form the bottom closure of the front flue box of the boiler. In the illustrated embodiment of the invention, plates 45 and 46 are bridged by spaced enclosure members 48 and 49, welded to the members 45 and 46 with the centrally located opening on top of the header being mated with a similarly sized opening 41 in the bottom of the flue barrel 29. This arrangement provides water circulation means so that the welding of all edges to those of the abutting member gives a completely sealed and water tight header joined for water circulation to the side water legs and to the flue barrel at the front and at the rear.

The front and rear headers 43 and 44 described above are attached to the lower part of the flue barrel 29 with

the front opening 41 of the barrel in alignment with the top opening of the front header 43 and the rear opening 42 of the flue barrel in alignment with the top opening of the rear water header 44. The flue barrel is preferably welded to both the front and rear headers to form water-tight compartments therebetween. A coupling 40 connects the opening 39 on the top side of the flue barrel 29 with the opening 28 of the inner shell 11 to provide means for the flow of water upwardly from the flue barrel into chamber 13 defined by the outer and inner shells 10 and 11 respectively.

For convenience in description of this invention, the outer shell structure was first described and then the inner-structure including the front and rear water headers attached to the flue barrel were described. In actual practice however, the flue barrel 29 and the front and rear headers 43 and 44, would normally be assembled, then the outer and inner shells would be assembled and joined to each other. The combined shells would then be positioned spanning the flue barrel with its complete assembly of flues, flue heads and attached transverse bottom connected headers. The shell assembly would be welded to the flue barrel assembly along the edges of the bottom water headers and along the common edges of circulation connection 40 joining openings 39 and 28. Upper water chamber 13 is then closed at each end by the attachment of plates 24 and 25 previously mentioned.

With the boiler assembled as described above, it will be observed that the inner shell 11 extends beyond the outer shell and the flue barrel and forms together with the flange 47' of the front water header, the sides of the front opening or flue box of the boiler. The front flue box is preferably closed by a suitable plate cover 50, removably secured by bolts 51, or other suitable fastening means. The rear portion of the flue barrel 29 in the instant embodiment of the invention extends beyond the rear edge of shell 11 and the gas passage space between the flue barrel and the inner shell 11 is closed gas-tight by a plate 25. The smoke outlet for the boiler may be arranged in any desired manner and may comprise an external housing or smoke box 50' secured to rear closure plate 25.

With the boiler as described above, provision is made for a separate combustion chamber, denoted in the drawings by the numeral 53. This chamber may be of any suitable construction, such as a steel shell lined with a suitable refractory material and the boiler in accordance with the invention is fixedly secured to the top surfaces of the combustion chamber. If desired, however, the four water legs of the boiler may be elongated to provide an integral water-walled combustion chamber or the sides of the outer shell 10 may be extended downwardly beyond the bottom of the water leg to the floor to form an integral dry supporting base. In addition, while the various elements such as the outer and inner shells 10 and 11 have been described as being one-piece elements, it is apparent that by welding they may be fabricated of smaller pieces of material. For instance, the top curved sections of the outer shell and of the inner shell, 10 and 11, respectively, may be formed of semi-circular members such as longitudinal halves of steel pipe and welded to flat side plates and the front and rear closure sections 24 and 25 may be formed of three or more separate elements in order to conserve material by eliminating wastage due to cutting the single closure pieces to the proper shape.

According to the invention, the flue barrel 29 is spaced from the inner shell 11 to provide for the flow of combustion gases from the combustion chamber below to the space about the outside of the flue barrel, and then to the front flue box where the gases are directed rearwardly through flues 31 in the flue barrel. This arrangement provides an exceedingly long travel for the gases of combustion and increases the transfer of heat to the water within the flue barrel and the side water legs between the shells. Moreover, the gases in their passage directed

about the flue barrel give up heat directly to the water in the water chamber 13 by virtue of the effectiveness of the upper surface of inner shell 11.

Another advantage of this boiler construction is the provision for the free flow of water between the several elements. The heated water in the side water legs flows directly upward into chamber 13 with replacement water currents from chamber 13 flowing downwardly along the unheated outer sides of shell 10. Water in the front and rear transverse headers 43 and 44 rises into the flue barrel through openings 41 and 42 and thence upwardly past the pointed bottom ends of the flues, then between the narrow waterways between the flues and along the inner contour of the flue barrel and converging at the top of the flue barrel above the pointed tops of the flues after having traversed the contained heating surfaces to flow thence through the circulation connection 40 into the upper water chamber 13. The front and rear transverse headers receive their water circulation from the side water legs through common openings 26 and 27.

By reason of the improved structure and design of the boiler complete simplicity is attained together with improved operation and fuel economy and the elimination of complicated and extensive water circulation conduits and other piping either within the boiler or external thereto.

When the boiler is used with hot water or steam heating systems, the return lines of the system would be connected to one or more of the openings 18 of the boiler while the flow header would be connected to the appropriate opening 17. Other openings 17 are for safety valve and steam or water gauges. In reverse flow hot water heating systems using forced pump circulation of the hot water through the system, the return connection may be made equally well to a connection 17 at the top of the boiler and the outwardly flowing water can be fed to the system piping through one of the lower connections at 18. In addition one or more drain cocks or valves may be connected to other openings 18 (Fig. 1) for the removal of sludge settling in the water legs while the opening 18' in the rear plate 25 may be used as a clean out or for attachment of a low water control. It will be observed that in view of the substantially unimpeded water circulation between the several elements that sludge accumulation if any will be carried to the water legs of the boiler from whence it can be easily blown off through the openings provided.

To increase the heat transfer efficiency of the flue gases as they pass through the boiler, steel baffle plates 54 and 55 singly or in combination may be placed in the side gas passages to baffle and divert the combustion gases between the flue barrel and the inner shell for a longer period of time by narrowing the exit opening between the barrel and the shell. This increases the gas velocity and length of gas travel and the heat transfer is thereby increased by more intimate scrubbing contact with the traversed heating surfaces. For convenience the broken arrows in each figure are denoted by the letter A indicate the flow of combustion products while the solid arrows B indicate the flow of water.

Another advantage of the invention is the arrangement of the elements which greatly facilitates internal inspection, access and installation of water heating coils for so-called tankless heaters and other purposes. This end is attained in the illustrated embodiment through the provision of a relatively large opening 60 in the front wall 24 which is closed by a plate 61 that may be secured in place by bolts 62 or other suitable fastening means. The holes 63 in the front and rear walls 24 and 25 are for the purpose of attaching lifting facilities in the manufacture and installation and the openings 64 in the wall 24 are for the attachment of a water level sight glass 65 when the boiler is used for the generation of steam.

Under certain conditions it may be desirable to provide an additional access or cleanout opening which in the illustrated embodiment of the invention is closed by

a plug 67. This opening may be used as an alternate water feeding and return connection in which case the transverse headers 43 and 44 may be omitted and the manufacturing cost of the boiler reduced.

While only one embodiment of the invention has been illustrated and described, it is apparent that other modifications, alterations and arrangements may be made without departing from the true scope and spirit thereof.

What is claimed is:

10. A boiler comprising an inverted, substantially U-shaped elongated hollow outer member, a U-shaped inner member spaced from said outer member, the inner surfaces of said inner member forming a fireside surface, a hollow elongated tubular member having gas conveying flues extending therethrough, the last said member being disposed between the legs of said U-shaped inner member and in spaced relationship to said fireside surfaces thereof, means closing the opening between one end of said tubular member and the adjoining end of the U-shaped inner member, a flue box closure on the other end of said U-shaped inner member enclosing the adjoining end of said tubular member, water circulating means coupling the upper side of said tubular member with the adjoining part of said U-shaped inner member and transversely positioned water circulating means within the boiler and beneath the tubular member, the last said circulating means coupling the under side of said tubular member with the lower part of said U-shaped inner member and wherein the last said means comprises at least one hollow transverse member disposed beneath one end of said tubular member and secured in sealed, water circulating relationship to said tubular member and to the lower portion of said U-shaped inner member.
20. A boiler comprising an inverted, substantially U-shaped elongated hollow outer member, a U-shaped inner member spaced from said outer member, the inner surfaces of said inner member forming a fireside surface, a hollow elongated tubular member having gas conveying flues extending therethrough, the last said member being disposed between the legs of said U-shaped inner member and in spaced relationship to said fireside surfaces thereof, means closing the opening between one end of said tubular member and the adjoining end of the inner U-shaped member, a flue box closure on the other end of said U-shaped inner member enclosing the adjoining end of said tubular member, water circulating means coupling the upper side of said tubular member with the adjoining part of said U-shaped inner member and transversely positioned water circulating means within the boiler and beneath the tubular member, the last said circulating means coupling the under side of said tubular member with the lower part of said U-shaped member and wherein the last said means comprises at least one hollow transverse member disposed beneath said tubular member and secured in sealed, water circulating relationship to said tubular member and to the lower portion of said U-shaped inner member.
30. A boiler comprising an inverted, substantially U-shaped elongated hollow outer member, a U-shaped inner member spaced from said outer member, the inner surfaces of said inner member forming a fireside surface, a hollow elongated tubular member having gas conveying flues extending therethrough, the last said member being disposed between the legs of said U-shaped inner member and in spaced relationship to said fireside surfaces thereof, means closing the opening between one end of said tubular member and the adjoining end of the inner U-shaped member, a flue box closure on the other end of said U-shaped inner member enclosing the adjoining end of said tubular member, water circulating means coupling the upper side of said tubular member with the adjoining part of said U-shaped inner member and transversely positioned water circulating means within the boiler and beneath the tubular member, the last said circulating means coupling the under side of said tubular member with the lower part of said U-shaped member and wherein the last said means comprises at least one hollow transverse member disposed beneath one end of said tubular member and secured in sealed, water circulating relationship to said tubular member and to the lower portion of said U-shaped inner member.
40. A boiler comprising an inverted, substantially U-shaped elongated hollow outer member, a U-shaped inner member spaced from said outer member, the inner surfaces of said inner member forming a fireside surface, a hollow elongated tubular member having gas conveying flues extending therethrough, the last said member being disposed between the legs of said U-shaped inner member and in spaced relationship to said fireside surfaces thereof, means closing the opening between one end of said tubular member and the adjoining end of the inner U-shaped member, a flue box closure on the other end of said U-shaped inner member enclosing the adjoining end of said tubular member, water circulating means coupling the upper side of said tubular member with the adjoining part of said U-shaped inner member and transversely positioned water circulating means within the boiler and beneath the tubular member, the last said circulating means coupling the under side of said tubular member with the lower part of said U-shaped member and wherein the last said means comprises at least one hollow transverse member disposed beneath one end of said tubular member and secured in sealed, water circulating relationship to said tubular member and to the lower portion of said U-shaped inner member.
50. A boiler comprising an inverted, substantially U-shaped elongated hollow outer member, a U-shaped inner member spaced from said outer member, the inner surfaces of said inner member forming a fireside surface, a hollow elongated tubular member having gas conveying flues extending therethrough, the last said member being disposed between the legs of said U-shaped inner member and in spaced relationship to said fireside surfaces thereof, means closing the opening between one end of said tubular member and the adjoining end of the inner U-shaped member, a flue box closure on the other end of said U-shaped inner member enclosing the adjoining end of said tubular member, water circulating means coupling the upper side of said tubular member with the adjoining part of said U-shaped inner member and transversely positioned water circulating means within the boiler and beneath the tubular member, the last said circulating means coupling the under side of said tubular member with the lower part of said U-shaped member and wherein the last said means comprises at least one hollow transverse member disposed beneath one end of said tubular member and secured in sealed, water circulating relationship to said tubular member and to the lower portion of said U-shaped inner member.
60. A boiler comprising an inverted U-shaped outer shell, a second inverted U-shaped inner shell spaced within the first shell to provide relatively narrow water compartments between the legs of said U-shaped shells and a relatively large compartment between the upper surfaces of said shells, means sealing the front, bottom and rear open end areas between said shells, an elongated tubular member including at least one water jacketed fire flue therein disposed within and spaced from said inner shell to provide a first gas passage, a front closure closing the area defined by the inner shell and spaced from said tubular member to provide a second gas passage therebetween communicating with the first gas passage, rear closure means closing the area between the inner shell and said tubular member, a combustion chamber beneath said tubular member and communicating with said first gas passage, said tubular member spanning said
70. A boiler comprising an inverted U-shaped outer shell, a second inverted U-shaped inner shell spaced within the first shell to provide relatively narrow water compartments between the legs of said U-shaped shells and a relatively large compartment between the upper surfaces of said shells, means sealing the front, bottom and rear open end areas between said shells, an elongated tubular member including at least one water jacketed fire flue therein disposed within and spaced from said inner shell to provide a first gas passage, a front closure closing the area defined by the inner shell and spaced from said tubular member to provide a second gas passage therebetween communicating with the first gas passage, rear closure means closing the area between the inner shell and said tubular member, a combustion chamber beneath said tubular member and communicating with said first gas passage, said tubular member spanning said

combustion chamber, baffle means closing the opening between the lower front portion of said tubular member, the inner surface of said inner shell and said combustion chamber to direct the products of combustion produced in said combustion chamber upwardly into the first gas passage and about said tubular member, said combustion products then moving forwardly into the second gas passage then through said tubular member for discharge to a flue, and water circulating means coupling the tubular member with said large water compartment.

4. A boiler comprising an inverted U-shaped outer shell, a second inverted U-shaped inner shell spaced within the first shell to provide relatively narrow water compartments between the legs of said U-shaped shells and a relatively large compartment between the upper surfaces of said shells, means sealing the front, bottom and rear open end areas between said shells, an elongated tubular member including at least one water jacketed fire flue disposed within said inner shell and spaced therefrom to form a gas passage, at least one hollow transverse member disposed beneath one end portion of said tubular member and secured in sealed, water circulating relationship to said tubular member and to the lower portion of said U-shaped inner member, a combustion chamber beneath the tubular member with said tubular member spanning said chamber, said chamber being in communication with said gas passage, baffle means closing the opening between the lower front portion of the tubular member and said inner shell to direct the products of combustion produced in said combustion chamber upwardly and about said tubular member, said combustion products then moving forwardly for discharge through said tubular member, and water circulating means coupling the tubular member with said large water compartment.

5. A steel plate flue boiler comprising an inverted, substantially U-shaped outer shell having coplanar leg portions and a connecting top portion, a second substantially U-shaped shell generally symmetrical but smaller than the first said shell and disposed within the first shell and having at least the front edge extending appreciably beyond the corresponding front edge of the first shell, means sealing the shells one to the other to form a watertight compartment therebetween including a relatively large upper water chamber and relatively narrow co-planar water leg chambers, an elongated tubular water chamber spaced from the inner surface of said inner shell with the front edge in at least close proximity to the plane of the front edge of said outer shell, said chamber including at least one fire flue extending longitudinally through the said chamber, means closing the front of the inner shell, baffles between the lower front portion of the tubular member and the inner shell, means on the other end of said inner shell closing the space between the inner shell and the tubular member and water circulation means coupling the tubular chamber and the chamber defined by the first and second U-shaped shells.
